UNITED STATES PATENT OFFICE.

JOHN COUNTER, OF ELIZABETH, NEW JERSEY.

WATCH AND CLOCK HOLDING CASE.

1,154,382.

Specification of Letters Patent. Patented Sept. 21, 1915.

Substitute for application Serial No. 623,987, filed April 28, 1911. This application filed June 25, 1913.
Serial No. 775,815.

To all whom it may concern:

Be it known that I, JOHN COUNTER, a citizen of the United States, and resident of Elizabeth, in the county of Union and State 5 of New Jersey, have invented certain new and useful Watch and Clock Holding Cases, of which the following is a specification.

The objects of this invention are to construct a case that will securely hold a watch 10 or other time piece; that will protect the same from injury, and also from dust, or moisture and the elements, and insulate the same from extreme effects of heat and cold; to provide means whereby the case and its 15 contents may be almost instantaneously secured to a dash-board, window frame, or other parts of an automobile or a car vestibule, so that it will be in a position for instant reference at any moment, or be as 20 quickly removed therefrom; also to provide means whereby the case and its contents may be held either in a vertical or inclined position as desired; and lastly to provide means whereby the case may be locked in 25 position so that it cannot be easily tampered with or stolen. I obtain these objects by means of the construction hereinafter described, shown in the accompanying drawings and specifically pointed out in the claim 30 annexed hereto.

In the drawings, which form a part of this specification, and in which similar letters of reference refer to similar parts wherever they occur, Figure 1 is a side elevation, partly in section showing a case held in an adjustable inclined position, also one form of base-piece for holding and supporting the case; and a locking plate F' with a recess f² for receiving the post f, formed in- 35 tegral with the back F. Fig. 2 is a vertical section of another form of base-piece and fastening means, the lower part of the case being broken away; Fig. 3 is a vertical section of another form of base-piece and fas- 40 tening means, which is adapted to hold the case in a fixed inclined position; Fig. 4 is a detail view of a spring thumb-piece which may be adapted to Figs. 2, 3, and 4 if required to supplant the square headed screw 45 construction; Fig. 5 is a detail sectional view on the line X—X of Fig. 1; Fig. 6 is a detail view of the method of fastening and holding the case in an inclined position, as 50 shown in Fig. 1.

In carrying out my invention, I form a 55 case A preferably of metal or of other suitable material, having a hollow body portion B, which is shaped to conform more or less exactly to the shape of the watch or other time piece C, and which may have a lining 60 of felt, cloth or other material C' (see Fig. 1) to prevent injury to the case of the watch or time-piece.

The case A is provided with a head D, which is preferably made integral with the 65 body portion B, and is shaped to receive means for suitably securing the case A to a base or bracket piece such as G', secured in any desired manner as by screws or bolts, to the supporting body, such as the dash-board 70 or window-frame of an automobile, or the stanchion of a trolley car.

The case A is provided with a glass front E, which may be secured to the case in any suitable manner, so that the face of the 75 watch or time-piece will be visible at all times. If desired the front E may be formed of glass lens, so that the characters on the face of the watch or time-piece will be considerably magnified, and rendered 80 more clearly visible.

The hollow body portion B is closed by a back-piece F, which is preferably screw-threaded, and engages with a corresponding screw-threaded portion in the back of the 85 body B, provision being made that the back-piece F may be screwed into the back of the body B, a sufficient distance to clamp the watch or time-piece C between the said back-piece F, or the lining C' placed in the said 90 back-piece and the front walls b of the body portion B, so as to prevent undue movement of the watch in the case A.

A base-piece G, preferably in the form of a partly hollow casting, as is clearly shown 95 in Figs. 2 and 3, may be secured to the dash-board, window casing, or some other convenient part of an automobile or other vehicle, and serve as the support for the case A. A socket g is formed in the upper sur- 100 face of the base-piece G, and is adapted to receive the head D of the case A. A square-headed screw H engaging in screw-threads suitably formed in central openings in the base-piece G and head D, secures the case A 105 to the base-piece G, the square head of the screw H being contained within a cup-like depression h, in the head D, in such manner

that its upper surface is below the walls of said depression, so that the screw can only be turned by a suitably formed wrench or key H' passing between the head of the screw and the walls of the depression.

In some cases, as for example where the case A is to be used by a motorist, it is desirable that it be held in an inclined position, so that the face of the time-piece will be 10 presented at right angles to the line of vision of the user. In such case, the base-piece G^2 is provided with a lug inclined at the proper angle as shown in Fig. 4, and the back piece F is provided with a post f , 15 preferably formed integral therewith, which in turn may be supported from the base G^2 attached to the automobile in proper position therefor.

A modification of the locking means is 20 shown in Fig. 3, in which the head D has a central opening d to permit of the passage of a plunger-pin J, which is provided with a cylindrical guide-piece j' at its outer end and the piece j' working slidably in a cylindrical socket formed in the head D on the outside of the opening d . A central opening J^2 and slots 1 and 2 are formed in the bottom of the socket g , of the base-piece G^2 , and a cross pin j^2 is passed through the end j^3 of 30 the plunger-pin J. A spiral spring K is interposed between the opposite ends of the depression h and the cylindrical portions j' , and surrounds the plunger-pin J. Indents 3, 4, are formed in the bottom of the base-piece G^2 between the slots 1, 2, as shown in Fig. 5. In this construction, the head D may be secured to the base-piece G^2 , by depressing the plunger-pin J against the action of the spring K, and passing the cross-pin j^2 through the slots 1, 2, and partially revolving the pin J until the ends of the cross-pin j^2 fall into the indents 3, 4, when upon the pin J being released the case A 40 will be held in position upon the base-piece 15 G^2 until the plunger-pin is again depressed, and rotated a sufficient distance to permit of the cross-pin passing out of the slots. If desired, the plunger-pin J may be provided with a square-head H^2 instead of the thumb-piece J' , shown in Fig. 4, and be operated 50 with a suitable wrench or key, as shown in Figs. 3 and 2.

In Fig. 6, I show a modified form of fastening means for holding the case at any desired inclined position, this form being applied to Fig. 1. In this form the base-piece G' is provided with a lug 5, projecting at a right angle therefrom. To the lug 5 is secured a toothed member 6. A block 12 carries the toothed member 8, which is adapted to engage with the toothed member 6. Adjustment of the position of the block 12 can

be made by moving the toothed members 6, 8, with relation to each other.

The boss 7 has a cup like depression 9, 65 adapted to receive the square-head of a set screw 10, which engages in screw-threaded central openings in the members 6, 8, and secures these parts together in their adjusted positions. The block 12 has a screw-threaded opening 11, and the head D of the case is secured to the said block by the screw H, as before described.

The cup-like depression in the head D of the case A is provided with an elastic rubber insertion 13 which absorbs the vibrations from the vehicle and also serves as a non-conductor of magnetism from electrical currents which would be transferred through the bent pin 14. 75

The bent pin 14 passing through the elastic rubber insertion 13 is fastened at the bottom and top by split coppers 15, the bent pin 14 passing through and serving as a pivotal center for the clamp arms L and the spring 85 16, whose purpose is to close the jaws of the clamp tightly on any convenient projection in view of the operator. 80

If desired, rubber or other non-conducting material may be interposed between the head D and the socket g , and may surround the screw H or plunger-pin J, to absorb vibrations, and to insulate the case A from electrical currents. The case A and head D may conveniently be formed in one integral 95 piece of any suitable material, and I have found that aluminum is well suited for the purpose, as it is light, does not corrode, and is attractive in appearance.

The subject matter of this application is 100 a substitute for that contained in my prior abandoned application bearing Serial Number 623,987, filed April 28, 1911.

Having now described my invention what I claim as new and desire to secure by Letters Patent is:— 105

A case for holding a time piece, comprising in combination, an integrally formed head and body having an aperture at the front and back thereof, a transparent closure 110 for said front aperture, a cover for said back aperture, said cover serving as a clamping means for retaining the time piece in position, a base adapted to support said head and body, means for locking said head and body to said base, and a supplemental support extending from said body to said base. 115

Signed at Elizabeth, in the county of Union and State of New Jersey, this twenty-third day of June, A. D. 1913.

JOHN COUNTER.
